FEED WATER HEATER

John M. Shimer, Dallas, Tex., assignor to Oil
Well Supply Company, Dallas, Tex., a corpora-
tion of New Jersey

Application July 11, 1935, Serial No. 30,909

1 Claim. (Cl. 261—34)

My present invention relates to apparatus for heating feed water for boilers by means of exhaust steam, and is an improvement on my Patent No. 1,964,710 of June 26, 1934.

In the feed water heater of the above patent, cold water was supplied by a pump to a heating chamber into which the exhaust steam was admitted for contact with the water, and the amount of water admitted to this heating chamber was controlled by a float valve. When the level of the water in the heating chamber rose to a predetermined limit, the admission of cold water was closed and the pump was stopped by the stopping of the flow of water therefrom. Although the pump was stopped, a full head of steam was applied at all times to the pump. This resulted in considerable waste of steam, and in other disadvantages.

These disadvantages are obviated by my present invention in which when the level of water in the heating chamber rises to a predetermined limit it acts to shut off the supply of power to the cold water feed pump, thus avoiding waste of power and also avoiding maintenance of pressure on the line to the heating chamber.

The various features of the invention are illustrated, by way of example, in the accompanying drawings, in which—

Fig. 1 is a side view of a heating chamber and of a pump and power driving means therefor embodying a preferred form of the invention.

Fig. 2 is an end view of the pump taken from the left of Fig. 1.

Fig. 3 is a vertical sectional view on line 3—3 of Fig. 1 through the heating chamber.

Fig. 4 is a plan view of the heating chamber and steam supply to the pump driving engine or power, and

Fig. 5 is a vertical view of the heating chamber taken on line 5—5 of Fig. 1.

In my invention steam is admitted to the heating chamber and water is sprayed through the steam until it accumulates to a predetermined level. Water is supplied to the heating chamber by a pump driven by suitable power means as, for example, a reciprocating steam engine. When water accumulates to a predetermined level in the heating chamber it lifts a float which, in turn, interrupts the supply of power or steam to the pump driving engine. Thereupon the pump stops and no further water is supplied to the heating chamber until sufficient water is removed to lower the level, whereupon the pump again supplies water to the chamber until the float is again lifted to its predetermined level.

In the specific embodiment illustrated in the accompanying drawings steam, which may be exhaust steam, is supplied from a supply pipe 10 to a heating chamber 11. It is directed by means of a deflector 12 and a baffle 13 across the upper end of the heating chamber so as to be brought into contact with water sprayed downwardly from an inlet valve 14. Any water that may be formed in the inlet pipe 10 by condensation of steam may pass through an opening 15 in the deflector 12 downwardly over the baffle 13.

Water is supplied to the inlet valve 14 from any suitable source by means of a pump 16 driven by a suitable power such as the reciprocating steam engine 17. Water is drawn into the pump 15 through an inlet pipe 18 and is forced from opposite ends of the pump into a pipe 19 and thence through a passage 20 extending upwardly and over the top of the chamber 11. From the passage 20 water passes in an expanding annular stream or spray through the valve 14, which is an inwardly opening spring operated check valve. The water thus sprayed into the heating chamber 11 comes into direct contact with the steam admitted through the pipe 10 and is thereby heated. The heated water collects in a pool or mass 21 in the lower part of the heating chamber 11 from whence it is withdrawn through an outlet pipe 22 to a force pump 23 which supplies the heated water to a boiler. Steam is supplied for driving the engine 17 from a supply pipe 24 through a shut off valve 25 in a branch pipe 26 which also contains a control valve 27. From the control valve 27 the steam passes through a pipe 28 and shut off valve 29 to the steam cylinder of the engine 17. Exhaust steam from the engine 17 as well as that from an engine 30 for driving the feed water pump 23 returns through an exhaust pipe 31 to the steam supply pipe 10.

The control valve 27 is actuated or controlled by the level of water in the heating chamber 11 through a float 32. The float 32 rises and falls with changes in the level of heated water in the chamber 11. This motion is transmitted by a crank arm 33 secured to the float to a rock shaft 34 which extends through a stuffing box 35 in the wall of the chamber. The movements of the rock shaft 34 are transmitted through a lever 36 outside of the chamber 11, and a link 37 to a lever 38 pivoted by a link 39 to the lower end of the valve 27. Movement is transmitted from the lever 38 through a valve stem 40 to a valve piston 41 in the valve 27. As the float 32 rises, it lifts the levers 36 and 38 and forces the valve piston 41

41 upwardly to restrict or interrupt the flow of steam through the valve 27 to the engine 17. As water is withdrawn from the chamber 11 the float 32 falls, lowering the levers 36 and 38 and the valve piston 41 and opens the valve for increased flow of steam to the engine 17. A by-pass pipe 42 and a control valve 43 enable the control valve 27 to be by-passed and steam to be admitted directly from the supply pipe 24 to the engine 17.

10 The pumps 16 and 23 and the engines 17 and 30 are mounted on a common pair of skids 44 in a compact unitary structure, but it will be understood that any other suitable mounting may be employed and that other pump constructions than that specifically illustrated may be employed.

It will be understood that the engine 17 is a small diameter engine as but little power is required to pump the water into the heating chamber 11. By controlling the supply of power to the pump 17 instead of controlling the flow therefrom under full power, waste of power is avoided and also the loading of the pump 16 and the piping from this pump to the heating chamber with an excess of power by stopping the supply of water is avoided and the operation of the apparatus thereby improved.

What I claim is—

Apparatus for supplying heated water which comprises a feedwater heater having a steam admission pipe, a steam actuated cold water pump for pumping cold water into the heater, means to divide said cold water as it enters said heater into intimate contact with steam admitted thereto to heat said water, a steam actuated hot water pump for pumping hot water from the heater, each pump having a steam cylinder and a pumping cylinder, manually actuated means for controlling the admission of steam to the steam cylinder of the hot water pump, means separate and individual of said manual means for controlling the steam supply to the steam cylinder of the cold water pump, said means comprising a steam supply valve subject continuously to full pressure steam, a float in said feedwater heater to open said valve when the water level therein falls below a predetermined level and to close it when the water level rises above a predetermined level, and a manually actuated throttle connected in parallel to said float operated valve for independent and conjunctive control of the admission of steam to the steam end of said cold water pump cylinder.

JOHN M. SHIMER.
